(57) **CLAIM**

The ornamental design for a strap for a cord management system, as shown and described.

DESCRIPTION

The present application relates to:

U.S. utility patent application Ser. No. 12/761,326 filed Apr. 15, 2010, entitled Cord Management System;

U.S. design patent application Ser. No. 29/368,755 filed Aug. 27, 2010, entitled Strap for a Cord Management System; and to

U.S. design patent application Ser. No. 29/368,754 filed Aug. 27, 2010, entitled Disc for a Cord Management System.

FIG. 1 is a perspective view of our new design of a strap for a cord management system;

FIG. 2 is a top view of the design of FIG. 1;

FIG. 3 is a bottom view of the design of FIG. 1;

FIG. 4 is a view of a first side of the design of FIG. 1;

FIG. 5 is a view of a second side of the design of FIG. 1;

FIG. 6 is a view of a third side of the design of FIG. 1;

FIG. 7 is a view of a fourth side of the design of FIG. 1;

FIG. 8 is another perspective view of the design of FIG. 1, the perspective view illustrating the embodiment when used in conjunction with an object; and,

FIG. 9 is another perspective view of the embodiment of FIG. 1, the perspective view illustrating the embodiment when used in conjunction with an object.

The broken lines showing elements of the strap for a cord management system in the above described figures are for illustrative purposes only and form no part of the claimed design.
